IRONING MACHINE SUPPORT

Herman A. Sperlich, Detroit, Mich.

Application November 29, 1940, Serial No. 367,736

6 Claims. (Cl. 248—13)

The present invention relates to folding supports for machines and is designed particularly for the support of home ironing machines, though not limited to use with such machines.

Among the objects of the invention is a support to which the machine may be secured and which, when the machine is idle, will occupy much less floor space.

Another object is a support in which the overall height when folded is not greater than in unfolded condition.

Another object is a support in which the machine supporting platform is rotated from the horizontal to the vertical and at the same time moved downward so that the upward end is considerably lower than if rotated only.

Still other objects will readily occur to those skilled in the art upon reference to the following description and the accompanying drawings in which

Figure 1 is a rear elevation with the frame member in partial section and showing the parts in "working" position.

Figure 2 is a similar view showing the parts in folded or "idle" position.

Figure 3 is a section on line 3—3 of Figure 1 and also showing a section through a part of the base member.

Figure 4 is a perspective view from the rear showing the unfolded support with an ironing machine; and

Figure 5 is an enlarged detail of the construction.

In the drawings, there is shown at 10 a suitable base provided with casters 11 and cut away in front as at 12 to provide foot space.

At the back of the base member is fixed an upright channel shaped frame member 15 open toward the front and closed at the upper end. This frame member 15 supports, through means to be described, a platform 16 carrying an ironing machine 17.

In the ironing machine shown, the ironer and platform are a unit, but it is obvious that any suitable platform may be used and some other form of machine mounted thereon, and in the following description the platform 16 will be referred to as though a separate element.

In the device as shown, the platform 16 is fixed to a partially circular plate 20 with an intervening guard or cover plate 21, the latter being used to prevent accidental access by the operator or work to the mechanism lying within the open front member 15 when the support is in either folded or unfolded position.

At the center of the plate 20 is fixed a short post or shaft 25 which extends through the upper portion of a carriage designated as a whole by the numeral 26. This carriage 26 consists of an upper and a lower tray-like cross member, 26a and 26b, respectively, fixed to a vertically extending channel member 27. This latter is provided with stepped side flanges of which the outer risers extend alongside of the flanges of members 26a and 26b but are spaced therefrom. The shaft 25 passes through the bottoms of both members, 26a and 27, and is rotatable therein.

Between the side flanges of channel 27 and carriage members 26a and 26b are a plurality of rollers 32 mounted in said flanges and coacting with a pair of tracks 32a fixed vertically to the side flanges of frame member 15. A second set of rollers 33 is also carried by the carriage member 27 and arranged angularly as shown so as to coact with the outer part of plate 20. Also fixed to plate 20 is a gear segment 40, the toothed edge of which is concentric with shaft 25 and in position to coact with a rack 41 formed in one side wall of frame member 15, so that when the platform 16 and plate 20 are rotated from the horizontal to the vertical position or vice versa, shaft 25 moves up and down through the rack and pinion action.

Since the weight of the platform 16 and whatever load it may carry is likely to be considerable, this is counterpoised by a strong compression spring 50 carried upon a telescoping rod 51 between a fixed abutment 52 carried thereby, and an abutment 53 fixed near the upper end of the rod. The lower end of the telescoping rod 51 rests in, and is maintained against swinging by, a V-shaped stirrup 51a fixed to the carriage 26.

This rod 51 is pivotally connected through a short link 55 to an arm 56 fixed to plate 20, and movement of these parts being controlled by the action of a second link 60 pivoted at one end to rod 51 coaxially with link 55 and at its other end to carriage 26 above shaft 25. These pivot points and the shaft 25 are so located that when the platform 16 is in vertical position, the spring is at maximum compression and the toggle, formed by rod 51 and link 60, is approximately but not quite straight, the same being true of the links when the platform is in horizontal position.

The positions of the links are shown best in Figure 5, the dotted line position being the down or vertical platform position.

In the operation of the device, as the platform 16 is rotated, the rack and pinion 40—41, of course will move the parts vertically, the shaft 25 moving

with the carriage 26, the rollers 33 maintaining the plate 20 properly spaced, and the rollers 32 and 34 serving to guide the carriage 26.

While the spring 50 will maintain the platform in its horizontal position, it is preferred to arrange on plate 20 and frame 15 suitable catch means (not shown in detail), operable by a handle 62, so that there is no tendency for rotation due to improper weight distribution during operation of the machine.

Now having described the invention and the preferred embodiment thereof, it is to be understood that the foregoing is merely descriptive, reference being had to the appended claims to indicate the scope of the invention.

I claim:

1. In an ironing machine support, a plate vertically arranged and secured to said machine, a shaft fixed to said plate, a frame member, a carriage vertically movable therein and in which said shaft is rotatably mounted, a vertically arranged rack on said frame, a gear segment fixed to said plate and arranged to mesh with said rack, and counterpoise means biased to cause rotation of said plate about said shaft as a center.

2. A support for machines of which the longest dimension is normally horizontal, said support comprising an upright frame member, means for mounting said machine upon said member including a rotatable element carrying said machine, a gear segment fixed to said element, a vertical rack carried by said frame member and meshing with said segment, whereby said element when rotated will be moved vertically, guide means for said element during such movement, and a spring counterpoise for said element and machine.

3. In a support, a platform, a channeled frame member open toward said platform, a vertically movable carriage in said frame, a shaft fixed to said platform and rotatably mounted in said carriage, means for moving said shaft and thereby said carriage, said means actuatable by rotation of said platform about said shaft as an axis, and a plurality of rollers carried by said carriage and

adapted to guide said platform and said carriage when said shaft is moved.

4. In a support, a platform, a channeled frame member open toward said platform, a vertically movable carriage in said frame member, a plate fixed to said platform and having fixed thereto a shaft rotatably mounted in said carriage, means for moving said shaft and thereby said carriage, said means actuatable by rotation of said platform about said shaft as an axis, and a plurality of rollers carried by said carriage and adapted to guide the latter in the frame member when the carriage is moved, and means carried by said carriage and tending to maintain said carriage in the upper portion of said frame.

5. In a support, a load carrying element, mounted for simultaneous rotative and vertical movement, counterpoise means including a spring movable vertically with said element and adapted to be compressed during said rotation and downward movement and thereby store energy to assist the reverse rotation and upward movement, and a toggle operatively connected to said element and said spring and arranged to be moved to substantially straight position as said spring is compressed and thereby aid in maintaining the said compression.

6. In a support in which the load-carrying element is constructed and arranged to be rotated and be simultaneously moved vertically, a stationary frame including a vertically arranged rack, said frame acting as a guide for said rotatable element in its vertical movement, a gear segment fixed to said rotatable element and meshing with said rack, and counterpoise means including a spring movable vertically with said element and adapted to be compressed during said rotation and downward movement, and thereby store energy to assist the reverse rotation and upward movement, and a toggle operatively connected to said element and said spring, and arranged to be moved to substantially straight position as said spring is compressed and thereby aid in maintaining the said compression.

HERMAN A. SPERLICH.
